UNITED STATES PATENT OFFICE.

HALVOR H. LYCHE, OF CHICAGO, ILLINOIS, ASSIGNOR TO THE ODIN COMPANY, OF CHICAGO, ILLINOIS, A CORPORATION OF ILLINOIS.

CLOTHES-WRINGER.

1,209,982.

Specification of Letters Patent. Patented Dec. 26, 1916.

Application filed February 12, 1916. Serial No. 79,769.

To all whom it may concern:

Be it known that I, HALVOR H. LYCHE, a citizen of the United States, residing at Chicago, in the county of Cook and State of Illinois, have invented certain new and useful Improvements in Clothes Wringers, of which the following is a specification.

My invention relates to wringers for washing machines, and has for one of its objects to improve the construction and increase the efficiency and utility of devices of this character. A further object of my invention is the provision of a novel safety device designed for the purpose of preventing the operator's hands being carried to and caught in the rolls of the wringer. My invention contemplates the provision of a unitary drainboard and endless belt conveyer for conveying articles of clothing to the rolls of the wringer, which is furthermore constructed to shed or convey water back to its source irrespective of in what direction the wringer is operated.

These, together with such other objects as may hereinafter appear, or are incident to my invention, I attain by means of the construction illustrated in preferred form in the accompanying drawings, wherein:

Figure 1 is an end view of a wringer with my device attached and a portion of the wringer frame broken away to expose the mechanism to view. Figure 2 is a front view of the same. Figure 3, a perspective view embodying the preferred construction of my improvements, omitting the conveyer belt. Similar characters refer to similar parts throughout the several views.

The frame 1 and rollers 2 and 3 represent parts common to clothes wringers, while my safety devices and attachments consist of a pair of brackets 4, provided with screw holes 5, for mounting the same on the wringer; other holes 6, in the upper part of the brackets are located adjacent to and above the roller 3, for suitable hinge pins 7, on which are mounted guards 8 on each side of and extending the entire length of the roller.

The lower edges 9, of aforesaid guards come in contact with the surface of the roller 3, at a point in a line tangent to the periphery of said roller and passing through the center of the hinge pin 7.

In the cross section, or end view, each guard is approximately the contour of one-

half of a heart, suspended so that the preponderance of weight will be on the outside to insure the edges 9, being kept bearing against the roller and also to form an efficient guard.

The lever action thus obtained is effective in stripping any clothes which may for any reason adhere to the wringer roller; even to the extent of swinging away from the roller and directing the clothes thus caught down to the conveyer belt herein-after described.

To keep the guards central between the end frames of the wringer, I have shown spacers 10 near each end of the hinge pins 7.

The numeral 12 designates a drainboard provided with the sides 17 recessed at 18 to clear the lower wringer roll 2 and having a base sloping up from each end to a center ridge or watershed 16. Spaced rollers 13 are carried in the sides 17 and brackets 4 through the instrumentality of the bearing members 11 and the studs or pins 14, which latter extend through the bearing members 11 from the rollers 13 into the outer ends of the brackets 4. Passed around the rollers 13 is an endless belt conveyer 15 having its upper stretch disposed in the pass of the rolls 2 and 3 and whose lower stretch is located adjacently over the watershed of the drainboard.

Thus it is to be clearly understood that this construction is adapted to convey the water back to the side from which it came, without the added process of tilting the board, as is the case on former devices for this purpose when the rotation of the wringer is reversed. To secure my device more firmly to the wringer frame I have shown brackets 19 on the under side of the drain board abutting and fastened to same.

In operation the wet clothes are simply placed upon the conveyer belt 15, which carries them through the wringer rollers and discharges them at a convenient distance from the wringer.

It is obvious that the water pressed from the clothes will return on the inclined upper surface of the belt and that which drips through or over the sides of the belt, will be conveyed back on the sloping bed of the drain board and on that side of the watershed adjacent to the side of the conveyer carrying the wet clothes.

The guards 8, which prevent the hands

of the operator from the danger of being caught between the wringer rollers may be raised to the position indicated by broken lines in Figure 1 for the purpose of inspecting and cleaning the wringer rollers.

I am aware that prior to my invention, safety devices for clothes wringers have been made with conveying belts. I therefore do not claim such a combination broadly but I claim:

1. In combination, a wringer frame provided with upper and lower wringer rolls, a drainboard carried by the frame and having a base and side frame members extending

15 outwardly from each side of the frame, spaced rollers terminally carried by said outwardly extending side frame members, and an endless belt conveyer extending around the rollers and having its upper stretch disposed in the pass of the rolls and its lower stretch in juxtaposition with the base of the drainboard.

2. In combination, a wringer frame provided with upper and lower wringer rolls, 25 a drainboard carried by the frame having a base and side frame members, spaced rollers carried by said side frame members, and an endless belt conveyer extending around the rollers and having its upper stretch disposed in the pass of the rolls and its lower stretch intermediate the lower roll and the base of the drainboard, the upper stretch of the belt conveyer and the base of the drainboard substantially correspondingly inclined whereby to shed the water in a direction away from the rolls.

3. In combination, a wringer frame provided with upper and lower wringer rolls, a drainboard carried by the frame having 40 outwardly extending side frame members, spaced rollers terminally carried by said side frame members, and an endless belt conveyer extending around said rollers and having its upper stretch disposed in the pass of the rolls and its lower stretch below the lower roll, and a stripper guard member pivotally carried by said side frame mem-

bers and having its lower free edge portion extending toward the pass of the rolls to contact peripherally with the upper roll, 50 said edge portion slightly removed from the upper stretch of the belt conveyer.

4. In combination, a wringer drainboard comprising side frame members and a base connecting said members, spaced rollers 55 having bearing members projecting laterally through the side frame members, and attaching brackets extending longitudinally of the side frame members and constructed to terminally engage the projecting bearing 60 members of the rollers.

5. In combination, a wringer frame provided with upper and lower wringer rolls, a drainboard having an arched base constituting a water shed for said rolls and side 65 frame members therefor extending outwardly at each side of the wringer frame, spaced rollers terminally carried by said outwardly extending side frame members, an endless belt conveyer extending around 70 the rollers and having its upper stretch disposed in the pass of the rolls and its lower stretch extending horizontally and adjacently across the apex of the arched base, and means for detachably connecting the 75 drainboard to the wringer frame.

6. In combination, a wringer frame provided with upper and lower rotary wringer rolls, an endless belt conveyer having its upper stretch disposed in the pass of said 80 rolls and its lower stretch located below the lower roll, and a stripper guard member associated at its upper end with said frame and constructed to extend toward the upper stretch of said conveyer and then inwardly 85 toward the pass of the rolls, the lower edge portion of said member adapted to peripherally contact with the upper roll, substantially as and for the purpose set forth.

HALVOR H. LYCHE.
